UNITED STATES PATENT OFFICE.

HENRY V. SMITH, OF PLANTSVILLE, CONNECTICUT, ASSIGNOR OF ONE-HALF
TO GEORGE E. CRUTENDEN, OF SAME PLACE.

CONVERTIBLE SCREW-DRIVER AND BORER.

SPECIFICATION forming part of Letters Patent No. 274,042, dated March 13, 1883.

Application filed September 4, 1882. (No model.)

To all whom it may concern:

Be it known that I, HENRY V. SMITH, of Plantsville, in the county of Hartford and State of Connecticut, have invented new Im-
5 provements in Convertible Screw-Drivers and Borers; and I do hereby declare the following, when taken in connection with accompanying drawings and the letters of reference marked thereon, to be a full, clear, and exact descrip-
10 tion of the same, and which said drawings con-
stitute part of this specification, and repre-
sent, in—

Figure 1, a side view, presenting the screw-
driver; Fig. 2, a vertical central section; Fig.
15 3, same as Fig. 1, presenting the borer.

This invention relates to an improvement in an instrument for driving screws, the object being to combine in one instrument a device for boring the hole and a screw-driver, either
20 of which may be used as required; and it con-
sists in a handle carrying a blade pivoted in the handle, one end shaped to form a borer to make the hole for the insertion of the screw, the other end a screw-driver, and arranged so
25 that either end may be presented for work, the other inclosed within the handle, the handle constructed in two parts from cast metal, so as to form a central handle, within which the in-
active end of the blade will be inclosed, and
30 the two parts of the handle secured together by a transverse rivet, and the blade held in its active position by a collar sliding on the body of the handle, as more fully hereinafter described.

35 The handle is made from two parts, A B, divided in a vertical or longitudinal line, the two parts fitting together, and so that a rivet, C, inserted transversely through the head end will secure the two parts together. The lower
40 part of the handle has a central slot, D, formed half in each part, and opening to the right and left. In this slot the blade is hung upon a pivot, a. The blade is shaped at one end to form a screw-driver, E, and the other end to
45 form a borer, F, the blade arranged so as to

swing through the slot and present either end—
say as from the position in Fig. 1 to that in Fig. 3, or vice versa. The pivot through the blade and lower end of the handle serves to secure that end of the handle together; but as
50 the pivot is necessary to the blade, the pivot C is the only additional part required. The body of the handle from the lower end upward is made cylindrical, and on this cylindrical part is a sliding collar, G, and which, when
55 the blade is in the desired position, is moved down to near the lower end, where the blade corresponds in width to the diameter of the handle, and in that position, as seen in the several figures, it holds the blade and pre-
vents its turning upon the pivot; but when it
60 is desired to change the ends of the blade, the collar G is moved upon the body away from the lower end, as seen in broken lines, Fig. 1,
65 which leaves the slot free for the turning of the blade.

By this construction I am enabled to cast the handle with the slot, and also to cast the handle hollow without a core, and thus produce a very cheap handle, and with this convertible borer and screw driver I produce an article convenient for joiners and others.

I claim—

As an article of manufacture, the herein-
described screw-driver and borer, consisting
75 of the handle made in two parts, A B, slotted
transversely, divided longitudinally through
the slot, a blade hung upon a pivot in the lower
end of the handle, arranged to turn through
80 the slot and present either end outward, the
other end being in the slot within the handle,
the body of the handle cylindrical, combined
with a collar, G, arranged to slide upon the
body of the handle, and the two parts of the
85 handle secured together, all substantially as
described.

HENRY V. SMITH.
